EDWARD A. STIGGINS, OF BEVERLY, MASSACHUSETTS, ASSIGNOR TO UNITED SHOE MACHINERY COMPANY, OF PATERSON, NEW JERSEY, A CORPORATION OF NEW JERSEY.

JACK FOR SHOE-MACHINES.

974,202.

Specification of Letters Patent. Patented Nov. 1, 1910.

Application filed November 16, 1904. Serial No. 232,952.

To all whom it may concern:

Be it known that I, EDWARD A. STIGGINS, a citizen of the United States, residing at Beverly, in the county of Essex and Commonwealth of Massachusetts, have invented certain Improvements in Jacks for Shoe-Machines, of which the following description, in connection with the accompanying drawings, is a specification, like reference characters on the drawings indicating like parts in the several figures.

This invention relates to jacks for shoe machines and particularly to jacks for use in connection with lasting machines.

The invention is shown as embodied in a jack of the type in which the last within the shoe is fitted upon a movable last-pin and during the lasting operation is forced rearwardly into a heel-band which is thereby caused to embrace and clamp against the last the heel portion of the upper materials including the heel stiffener to conform these portions of the shoe to the side faces of the last and co-operate with other lasting instrumentalities, as, for example that shown in my earlier application Serial No. 127,116, in conforming the shoe stock to the bottom face and the edge of the last at the heel of the shoe, including the upper material and the counter.

In the preferred construction of jack herein shown a pivotally sustained last-pin is employed and the movement of the shoe into the heel-band is effected by means engaging the forepart of the last to rock the toe end of the shoe upwardly and rearwardly. In this movement of the shoe into the heel-band the angular relation of the shoe bottom to the edge of the heel-band is altered and as it is a matter of importance in the subsequent lasting operation that the edge of the heel-band shall occupy a position flush or parallel with the bottom of the shoe all the way around the counter, I have provided means for angularly moving the heel-band. As herein shown, the heel-band is pivotally supported near its front ends and at its middle rear portion is connected to a movable support by means of which it may be actuated in the direction of the height of the shoe to change the plane in which its upper edge lies. The heel-band which I prefer to employ is flexible or resilient and is normally held open with its ends spread apart wide enough to receive readily the

widest last for which the jack is adapted. The free front ends of the heel-band are supported by means adapted to permit the end portions of the band to close against the sides of the shoe when the shoe is pressed rearwardly into the band. In such rearward movement the shoe engages first the rear middle portion of the heel-band which yields until the end portions of the band have been drawn inwardly against the sides of the last. In this latter part of the movement of the shoe the friction between the end of the shoe and the rear middle portion of the band prevents relative vertical movement of these parts and the portion of the shoe adjacent to the ends of the band rises slightly with relation to the band, thus tending to draw the upper at these points downwardly away from the bottom of the last. To offset this movement of the portion of the shoe adjacent to the ends of the band I preferably connect the band to its pivotal supports at points located a short distance back from the front ends of the band so that when the heel-band is actuated to change the plane in which its upper edge lies the front ends of the band are raised.

In the illustrated embodiment of the invention the fore part of the shoe is engaged and the shoe is moved or rocked rearwardly into the heel-band to jack the shoe by means which includes a toe-band adapted to be actuated upwardly against and around the toe end of the shoe for wiping the upper toward the shoe bottom, and I have in this embodiment of the invention connected the toe-band with the movable support for the rear end of the heel-band in such a way that when the toe-band is raised and the shoe rocked rearwardly, the heel-band will be moved to change the plane in which its upper edge is located. By this arrangement I am enabled to position the shoe in the jack with its bottom flush or parallel with the upper edge of the heel-band and then by rocking the heel-band simultaneously with the shoe to maintain the heel-band and shoe in substantially the same plane. I preferably employ in combination with my movable heel-band a vertically movable and preferably yieldingly sustained last-pin, and I have also shown means co-operating with the yielding last-pin for positioning a shoe with its bottom face flush with the upper edge of the heel-band, what-

ever may be the size or height of the last within the shoe.

A further feature of my invention consists in an improved toe-band and in novel means for adjusting and actuating the toe-band.

Other features of the invention, including certain details of construction and combinations of parts, will be hereinafter described and pointed out in the claims.

Figure 1 is a side elevation of a jack embodying the present invention, the parts being shown by full lines in the position which they occupy before being actuated to jack the shoe, while the dotted lines show the relative positions of the toe-band, shoe bottom, and heel-band when the shoe has been jacked. Fig. 2 is a front elevation of the jack, certain parts being shown in section on the line 2—2 of Fig. 1. Fig. 3 is a rear elevation of the jack.

The jack comprises a base plate 1 upon which is guided the carriage 2 for supporting the toe-band 6 and the carriage 8 for sustaining the last-pin 10 and the heel or counter-embracing-band 12. The carriages are preferably adjustable toward and from each other for shortening or lengthening the jack by a right and left-threaded screw 14 which is secured against longitudinal movement in the base plate and is provided with an operating crank 16. The heel carriage 8 has ears 18, shown in dotted lines in Fig. 1, between which is pivoted a support 20 for the last-pin 10. A spring plunger 24 is mounted in the support at the rear side of the pivot and rests on the carriage for holding the support and last-pin normally tipped away from the heel band to enable the last to be readily placed on the last-pin. The carriage 8 is provided on either side with ears 34 to which are pivotally connected the opposite ends of a casting 37. Curved spring arms 40 are rigidly secured to the casting 37 and are pivotally connected at their upper ends to the end portions of the heel-band.

The spring arms are preferably formed so that they hold the end portions of the heel-band normally spread apart far enough to receive readily the widest last for which the jack is adapted. When pressure is brought to bear against the middle rear portion of the heel-band the arms yield inwardly to permit the end portions of the band to embrace and clamp the upper materials against the last. The middle rear portion of the band is connected by means of an adjustable support 42 with a lever 44 which is shown as fulcrumed at 46 to one of the spring arms 40. By actuating the lever 44 the band may be rocked in the direction of the height of the shoe about its pivotal connection with the supports 40 for changing the angular position of the band. As will be hereinafter more fully explained, the shoe is jacked by

rocking the shoe backwardly into the heel-band, the shoe moving about the pivotal connection of the last-pin with the ears 18, and in this movement the extreme rear end of the heel of the shoe is obviously lowered. 70 The heel-band may be operated by means of the lever 44 to maintain its upper edge parallel with the bottom of the shoe during this rocking movement. It is found in practice that as the shoe is rocked backwardly the 75 portions of the last adjacent to the front ends of the counter rise slightly, and if the end portions of the heel-band have not a corresponding movement there is a tendency to draw the upper at this point downwardly 80 away from the last bottom. To overcome this tendency and permit of the heel-band being moved in such manner that its upper edge may be maintained at all times flush or parallel with the bottom of the last I preferably locate the pivotal connection between the end portions of the band and the spring supporting arms 40 at a short distance back from the ends of the band, whereby when the band is rocked about said pivotal connections the front ends of the band rise enough to compensate for the slight rise of the last at the adjacent portion of the shoe. The casting 37, upon which the spring arms 40 are carried, is arranged to be moved manually about its pivotal connection with the ears 34 for the purpose of adjusting the heel-band toward and from the last-pin, and a spring pawl 36 engaging a ratchet 39 holds the casting in adjusted position. Means is 90 preferably provided for depressing the shoe, whatever its height, into a position in which its bottom face is flush with the upper edge of the heel-band. The shoe depressing means 95 comprises a yoke 41 having a contact piece 100 43 for engaging the bottom of the last. The yoke is pivotally connected to the operating handle 45, which when turned from the dotted line position in Fig. 1 to the full line position in said figure will draw the yoke 110 downwardly and cause the shoe and last-pin to be depressed into the position shown in full lines in Fig. 1.

The upright carriage 2 at the front end of the jack is provided with a guideway for a longitudinally movable post 50 to which is pivotally connected a carrier 52. To the downwardly curved rear end of the carrier 52 is attached a socket piece 54 having a screw-threaded guideway for receiving an 120 adjustable stop screw 56 upon the upper end of which rests the stem 58 of the toe-rest 60. The socket piece has in one side a slot which forms a guideway for a laterally projecting pin 62 which limits the movement of the 125 stem 54 in the socket piece and prevents rotation of the toe-rest. The toe-band is supported by a holder comprising a block 64 connected by a pivot pin 66 to the front end 130 of the carrier 52 and provided at its lower

end with laterally extending lugs 68 upon which are pivoted bars 70 for sustaining the curved spring arms 72 which are connected at their upper ends to the end portions of the toe-band. The middle portion of the toe-band is connected to the block 64 by links 73. The pivotal connection between the arms 72 and the block 64 permits the toe-band to swing from side to side to adapt its position to the position and shape of the toe ends of different lasts. The rear ends of the levers are connected by a right and left threaded adjusting screw 73 by which said bars together with the spring arms 72 upon the opposite sides of the jack may be moved toward or from each other for spreading or contracting the toe-band according to the width of the shoes to be jacked. The post 50 is provided with rack teeth 74 engaged by a pinion 76 carried by a shaft 78 which is journaled in a bearing extending from the carriage 2. An operating handle 80 is secured to the outer end of the shaft 78 and by depressing the handle the post 50, together with the toe-rest 60 and toe-band 6, may be raised for rocking the shoe rearwardly into the heel-band and wiping the upper on the toe portion of the last toward the last bottom. The lever carries a pawl 82 adapted to engage with ratchet teeth formed on a circular plate 84 attached to the outer end of the shaft bearing for locking the handle in adjusted position. A spring 86 connects the carrier 52 with the carriage 2 and tends to return the carrier and the parts supported by it to their lowest position when the pawl 82 is disengaged from the ratchet 84.

Preferably and as herein shown, means is provided for adjusting the toe-band angularly in a direction transverse of the last to adapt the toe-band for use with twisted lasts, in which the last bottom at one edge is higher than at the other edge. To this end the block 64 is formed with a bearing for a short shaft 90 having on its rear end an eccentric 92 located in a slot formed in the carrier 52. The shaft 90 is provided on its outer end with a hand wheel 94 the shank of which has a roughened surface 95 engaged by a spring pawl 96 for holding the eccentric in adjusted position. By turning the eccentric in one direction or the other the block 64 may be moved angularly about its pivotal connection 66 with the carrier 52 and thereby angularly adjust the toe-band in the direction of the width of the last. In this adjustment of the block 64 the opposite sides of the toe band are simultaneously moved vertically in opposite directions by means of the connections 72 and 73 between said block and the band.

It is desirable to move the heel-band about its pivotal connection with its supports 40 at the same time that the toe-rest and toe-band

are elevated for moving the shoe rearwardly into the heel-band, as by so doing the heel-band may be maintained continuously with its upper edge flush or parallel with the bottom of the last. To this end I have herein shown a connection between the post 50, by means of which the toe-rest and toe-band are elevated, and the lever 44, by means of which the heel-band is rocked. This connection is shown as comprising a bar 98 secured to the post 50 and arranged to slide freely through an elongated guideway in the front end of the lever 44, whereby the connection between the post and the lever is maintained in the various adjustments of the jack for long and short shoes. The heel-band might of course be arranged to be rocked independently of the operation of the toe-band, if so desired. The initial position of the heel-band may be varied by adjusting the support 42, which, to this end, is shown as made in two sections connected by a turn buckle.

In using the jack the carriages 2 and 4 are adjusted for the length of shoe to be jacked, and if the last is a twisted last, the toe-band is adjusted angularly by means of the hand wheel 94. The shoe is applied to the jack by fitting the heel end of the last onto the last-pin 10 and resting the forepart 95 of the shoe upon the toe-band, as shown in Fig. 1. The shoe depressing means is then moved into engagement with the bottom of the shoe and the operating handle 45 depressed from the dotted line position shown in Fig. 1 to the full line position shown in said figure for forcing the shoe downwardly until the bottom of the shoe is flush with the upper edge of the heel-band, the spring-sustained last-pin yielding to permit this movement of the shoe. The handle 80 is then depressed for raising the toe-rest 60 and toe-band 6, and in this movement the toe-band is raised along the sides and end of the shoe, wiping the upper materials 110 toward the shoe bottom until it reaches a position in which its upper edge is flush with the bottom of the last, and the band embraces the entire toe portion of the shoe for holding the upper in the position to which it has been wiped. Also by this same movement the shoe is rocked about the pivotal connection of the last-pin 10 with the ears 18, whereby the shoe is forced rearwardly into the heel-band. The shoe engages first with the middle rear portion of the heel-band and in its further rearward movement the spring arms 40 yield inwardly and cause the front ends of the heel-band to embrace the sides of the heel portion of the shoe. The rocking movement of the shoe obviously causes the extreme rear end of the shoe to move downwardly, but the connection between the post 50 and the lever 44 causes the heel-band to be rocked in the di-

rection of the height of the shoe, whereby the upper edge of the heel-band is maintained flush or parallel with the bottom of the shoe. The pawl 82 locks the handle 80 and therefore the several parts in the position to which they have been moved and the shoe depressing means may then be released and moved into an inoperative position, leaving the shoe ready to be presented to 10 the lasting machine or to any other mechanism by which the shoe is to be acted upon.

Having set forth the nature of my invention and fully described a construction embodying the invention in a preferred 15 form, I claim as new and desire to secure by Letters Patent of the United States:—

1. In a jack, means for supporting a shoe, a heel-band adapted to embrace the heel portion of the shoe, means for jacking the shoe 20 and means operated automatically during the jacking operation for actuating the band in the direction of the height of the shoe sustained by the supporting means.

2. In a jack, means for supporting a shoe, 25 a toe-band, a heel-band, and means connected with one end of the heel-band for rocking said band in the direction of the height of the shoe about an axis extending transversely of the shoe and located near 30 the other end of the band.

3. A jack, comprising a heel-band adapted to embrace the heel portion of a shoe, a toe-band adapted to embrace the toe portion of the shoe and means under control of 35 the operator for simultaneously rocking the two bands in the direction of the height of the shoe.

4. In an apparatus of the class described, 40 a heel pin for supporting a last, a heel-band, means for thrusting the last on the heel pin backwardly into the band, said apparatus having provision for tipping the heel-band during said backward thrust to compensate for the angular movement of the last about 45 the pivot of the heel pin.

5. In a shoe-supporting jack, a heel-band, means for supporting the heel-band, means for jacking the shoe, and means for actuating 50 said heel-band during the jacking operation to move its middle rear portion downwardly and its front end portions upwardly.

6. In a jack, a movably supported heel-band, means for supporting a shoe, means for rocking the shoe to force the heel portion 55 thereof into the heel-band, and means for maintaining the upper edge of the heel-band in a plane parallel with the bottom of the shoe during the rocking movement of the shoe.

60 7. In a jack for supporting a shoe, a heel-band, means to position the shoe with its bottom face parallel with the edge of the heel-band, means for moving the shoe angularly toward the heel-band, and means for actuating the heel-band to maintain its edge

parallel with the edge of the shoe during said angular movement of the shoe.

8. In a jack, means for supporting a shoe, a heel-band, and a toe-band, combined with means for actuating the toe-band to cause 70 it to embrace the forepart of the shoe and simultaneously actuating the heel-band in the direction of the height of the shoe.

9. In a jack, means for supporting a shoe, a heel-band, a toe-band, means for actuating 75 the toe-band to rock the shoe toward the heel-band, and connections between said actuating means and the heel-band whereby the heel-band is rocked in the direction of the height of the shoe.

10. In a jack for lasting machines, means 80 for supporting a shoe, a heel-band, a toe-band, and means for actuating the toe-band to wipe toward the shoe bottom the upper material on the toe portion of the last, and connections between said actuating mechanism and the heel-band whereby the heel-band is rocked in the direction of the height of the shoe.

11. A jack comprising a heel pin, a toe-rest, a pivotally supported toe-band and a heel-band pivotally supported in definite relation to the heel pin, in combination with means for rocking the heel-band in the direction of the height of the shoe to position 90 its upper edge relatively to the plane of the heel bottom.

12. A jack, comprising a heel pin, a heel-band, supports to which the front ends of 100 the band are pivotally connected, and means connected with the rear portion of the heel-band for adjustably sustaining the band in different angular positions with relation to its pivotal connections with its supports, combined with means for rocking said band about said pivotal connections, and other means for initially positioning the heel-band 105 and its supports with relation to the heel-pin.

13. A jack, comprising a heel-band, a toe-band, means for adjusting the bands toward 110 and from each other to adapt the jack for lasts differing in length, means for actuating the toe-band to rock the shoe, and means connecting said actuating means with the heel-band for rocking the heel-band, said means being arranged to maintain operative connection between the heel-band and the actuating means in different adjusted positions of the toe-band and heel-band.

14. In a jack, a toe-band, and means for 120 angularly adjusting said band as a whole transversely of the last about an axis located below the band.

15. In a jack for a last, a toe-band, a holder therefor adapted to move about an axis extending longitudinally of the last and below the forepart of the last, and means for adjusting said holder and band about said axis. 125

16. In a jack, a toe-band, a holder therefor adapted to move about an axis extending 130

longitudinally of the jack, and means for adjusting said holder and band about said axis, said means comprising an eccentric engaging said holder, a hand wheel for adjusting said eccentric, and means for holding the eccentric in adjusted position.

17. In a mechanism of the class described, a toe-band, and a holder therefor, comprising a member for supporting the middle 10 portion of the band and resilient arms movably sustained by said member and connected at their upper ends to the end portions of the band, said arms being arranged for lateral yielding movement to spread and 15 contract the band.

18. In a mechanism of the class described, a toe-band, and a holder therefor, comprising a member for supporting the middle 20 portion of the band and resilient arms secured to the end portions of the band and connected to said member for pivotal movement with relation thereto for spreading and contracting the band.

19. In a mechanism of the class described, 25 a toe-band, and a holder therefor, comprising a member for supporting the middle portion of the band, bars pivotally secured to said member at the opposite sides of the jack, spring arms carried by said bars for 30 supporting the end portions of the band, and means for adjusting said bars relatively for spreading and contracting the band.

20. In a mechanism of the class described, 35 end lasting means formed to embrace the end portion of a last and means for angularly adjusting said lasting means about an axis extending longitudinally of the last and located a substantial distance below the lasting means.

21. In a mechanism of the class described, 40 end lasting means, a block extending transversely of the last, supporting arms connecting said block and the lasting means, and means for actuating said block to adjust 45 the lasting means about an axis extending lengthwise of the last and located a substantial distance below the plane of the last bottom.

22. In a mechanism of the class described, 45 end lasting means, a block extending transversely of the last, upright arms connecting

said block and the lasting means, a pivotal support for the block, an eccentric operatively connected with the block, and means for turning the eccentric to adjust the block 55 and the lasting means about an axis extending lengthwise of the last.

23. In a mechanism of the class described, 60 end lasting means, a carrier, a transverse block pivoted to the carrier below the lasting means, arms operatively connecting the opposite ends of the block with said lasting means, and an adjusting device connecting the carrier and said block to turn the latter about its pivotal connection to the 65 carrier and, through said arms, to effect an angular adjustment of the lasting means about an axis extending lengthwise of the last.

24. In a mechanism of the class described, 70 the combination with a lasting means, its carrier, and two supporting arms for said lasting means, of a block to which the lasting means is connected by said supporting arms, and means for angularly adjusting the lasting means and block transversely of the last.

25. In a mechanism of the class described, 75 the combination with a lasting means, its carrier, and two supporting arms for said 80 lasting means, of a block forming a support common to both arms and mounted so as to be capable of angular oscillation transversely of the carrier and an eccentric engaging a fork of said block and under control of the operator to effect angular adjustment of the block.

26. In a mechanism of the class described, 85 the combination with a lasting means, its carrier, and two supporting arms for said 90 lasting means, of means operating through said supporting arms for angularly adjusting the lasting means about an axis extending lengthwise of the last.

In testimony whereof I have signed my 95 name to this specification in the presence of two subscribing witnesses.

EDWARD A. STIGGINS.
